Richard J. Cook

ATTORNEY

UNITED STATES PATENT OFFICE

ALBERT ARMSTRONG, OF SEATTLE, WASHINGTON

DRY-KILN CONSTRUCTION

Application filed December 27, 1926. Serial No. 157,246.

This invention relates to improvements in dry kiln construction, and more particularly to a roof construction for dry kilns that will provide maximum insulation and also give protection to the reinforcing steel contained within the roof.

More specifically stated, the object of the invention resides in the provision of a concrete and tile roof for dry kilns, wherein hollow tile of the interlocking type, laid in juxtaposition and in parallel rows, are used as an inside lining and provide continuous insulation across the entire inside surface of the roof; the tile also providing the forms for the formation of concrete beams and serving as means for insulating the latter and for protecting the reinforcing steel within the beams against the destructive action of acids and heat produced incidental to the drying of lumber in the kiln.

Other objects of the invention reside in the various details of construction and in the combination of parts as is hereinafter described.

In accomplishing these and other objects of the invention, I have provided the improved details of construction, the preferred forms of which are illustrated in the accompanying drawings wherein—

Figure 1 is a perspective view of a section of the dry kiln roof constructed in accordance with the present invention.

Figure 2 is a sectional view of the same, taken lengthwise of a drying chamber.

Figure 3 is a cross sectional view of the roof.

Referring more in detail to the drawings—

While the present invention is primarily intended for the construction of roofs for dry kilns, it is to be understood that it is not confined only to this particular use, as it is well adapted to side and end wall construction in dry kilns and for various other building purposes where insulation is desired or essential, such as in refrigerating plants or the like.

In forming the roof of the present character, the usual wooden forms are first erected between the vertical walls of the kiln and these forms support the roof until the concrete has sufficiently set. In the roof con-

struction, I use hollow tile of the character commonly known as interlocking tile and wherein each tile, as designated at 1, comprises a hollow, rectangular base portion 2, approximately six and one-half inches wide, 55 twelve inches long and four inches high, and which is provided lengthwise and centrally across the top surface with a hollow rib portion 3 about four inches wide and four inches high. The base portion of the tile is divided lengthwise by a vertical, centrally located web 2' and the rib portion is divided lengthwise by a horizontal, centrally located web 3'. The tile are laid upon forms in parallel rows, tightly together, as indicated in the drawing, so as to provide continuous insulation across the under side of the roof.

After the tile have thus been laid on the forms, reinforcing bars 4 of any desirable character are placed longitudinally within the spaces provided between the parallel rows of ribs and are supported in proper position by any suitable means, not shown, prior to the pouring of the concrete. Other reinforcing bars 5 may also be located transversely 75 of the rows of tile across the upper side of the ribs to give additional strength to the roof and to serve as means for preventing cracking.

After the concrete has been poured over the tile to fill the spaces between the rows of ribs and to cover the latter to a thickness of about three inches, it is troweled off smooth to provide for easy drainage.

It is readily apparent that with the tile so placed, the rows of ribs provide forms for the formation of the supporting beams 6 for the roof slab 7, and since the ribs of the tile are hollow as well as the base portions of the tile, each of these beams will be well insulated. This method of insulating prevents not only absorption of heat by the walls but also prevents damage to the reinforcing steel that is sometimes caused where such insulation is not provided by the action of the acid contained in the vapor arising from the lumber being dried within the kiln.

It is to be understood that tiling of various character other than herein shown or described may be used for this purpose, and

when tiling of the character shown is used it may have various proportions other than those herein stated and, for these reasons, I do not wish to be confined only to that shown and described.

5 It has been found that a roof so constructed gives perfect insulation and affords protection to the reinforcing iron to an extent that makes the present construction more serviceable and desirable than roof constructions commonly used.

10 Having thus described my invention, what I claim as new therein and desire to secure by Letters-Patent, is:

15 A lumber dry kiln roof comprising an under surface lining formed from hollow tile that are laid in juxtaposition and a concrete top surface overlying the tiling to a substantial thickness; said tiling having hollow, upstanding ribs formed thereon whereby they are supported and arranged in co-extensive relation to provide forms for the formation between them of concrete supporting beams integral with the top surface and reinforcing bars imbedded in the beams; said hollow tile construction being substantially a continuous one over the entire lower surface of the roof and forming a dead air space below the concrete top surface and supporting beams whereby absorption of acid by the concrete from lumber being dried is avoided and whereby roof drip caused by a differential in temperatures inside and outside the kiln is overcome.

20 30 35 Signed at Seattle, Washington, this 14th day of December, 1926.

ALBERT ARMSTRONG.
